UNITED STATES PATENT OFFICE.

THADDEUS J. FLYNN AND JOHN H. FLYNN, OF CAMBRIDGE, MASSACHUSETTS.

ROOF DRAIN.

Application filed December 5, 1925. Serial No. 73,446.

This invention relates to improvements in roof drains and has as its general object to provide a durable and substantial roof drain which may be installed in practically any 5 type of roof construction and connected or secured to any type of roofing.

Another object of the invention is to provide a roof drain which will be so constructed as to most effectually perform its function in 10 draining the water from the roof and conduct the same, without leakage, to the down pipe hub, or other fitting.

Another object of the invention is to provide a roof drain so constructed as to provide 15 against the condensation of moisture on the exterior of the shell thereof.

Another object of the invention is to so construct the roof drain that expansion and contraction, due to settling or shrinkage of 20 the roof structure, will be compensated for so that likelihood of leakage is reduced to a minimum.

In the accompanying drawings:

Figure 1 is a perspective view of the roof 25 drain embodying the invention.

Figure 2 is a detail vertical sectional view through the roof drain installed, the section being taken substantially on the line 2—2 30 of Figure 1, looking in the direction indicated by the arrows.

Figure 3 is a fragmentary perspective view illustrating a portion of the strainer cap of the drainer.

The roof drain comprises a unitary structure 35 which is illustrated in Figure 1 of the drawings and which includes a pan indicated in general by the numeral 1, and which is preferably made of soft sheet copper and pressed in one piece. This pan may be of the 40 rectangular form shown in Figure 1, or of any other desired form, and the same is provided centrally with an opening indicated by the numeral 2, in which the outer shell of the drain, to be presently described, is fitted. 45 The pan is to be disposed upon the surface of the roof, indicated by the reference letter R, with the opening 2 in approximate registration with the opening 3 which is provided in the roof or roof deck, to accommodate the 50 drain, and the pan is secured in any suitable manner, as for example, by nails 4 which are driven through the pan and into the deck of the roof. As previously stated, the drain is 55 designed to be employed in connection with any type of roof and for the purpose of compensating for expansion and contraction and

likewise to provide against any of the gravel or other roofing material entering the drain, the sheet of which the drain is formed is pressed to provide an upstanding bead 5 60 which is continuous and centrally located with respect to the margin of the pan and spaced from and surrounds the opening 2 in the pan. This bead is preferably of a gradually curved contour in cross section so that 65 it may spread under expansion or contract with the construction of the roof, and the said bead is of sufficient height to provide against any of the gravel or other roofing material, 70 which covers the upper surface of the pan outwardly beyond the bead, and which is indicated by the reference letter R', reaching that portion of the pan which is surrounded by the bead. Therefore, the bead defines or surrounds an area of the pan which is smooth 75 and not covered by the roofing material and over which the rain water may readily flow without any obstruction being offered to its passage from the pan into the drain proper. Likewise, inasmuch as none of the gravel or 80 other roofing material can reach this portion of the pan, there is no likelihood of the roofing material entering the shell of the drain.

The shell comprises an outer shell member 6 which is preferably of seamless copper tubing 85 and exteriorly of a diameter to fit relatively snugly through the opening 2 in the pan, the said shell section being provided at its upper end with a circumscribing outstanding flange 7 which rests upon the upper side of the portion 90 of the pan of the drain which is surrounded by the bead 5. The shell section 6 extends downwardly through the opening 3 and is flared at its lower end as indicated by the numeral 8, so as to fit within the socket 95 or bell 9 of a hub coupling 10 which may be of the straight or elbow type, as found expedient. In order to provide a watertight union between the shell section 6 and the hub 10, a packing 11 of oakum is tamped into the 100 space between the wall of the socket 9 of the hub and the lower end portion of the shell section 6 which fits within the socket, and a calking of lead, indicated by the numeral 12, is poured into the socket and completes the seal 105 between the parts, it being observed that the rim of the flanged lower end of the shell section 6 seats snugly against the inner surface of the said socket substantially at the shoulder 13 thereof. The shell further includes an 110 inner section which is indicated by the numeral 14 and is likewise of seamless copper tub-

ing but of a lighter gauge than the section 6. The section 14 comprises the inner section of the shell and the same is exteriorly of a diameter somewhat less than the internal diameter of the section 6 of the shell, the exterior diameter of the shell section 14, however, being substantially equal to the internal diameter of the hub 10 below the socket thereof, so that the lower end of the shell section 14 is adapted to fit snugly within the said hub. At its upper end, the shell section 14 is formed with an outstanding circumscribing flange 15 which rests flat upon the upper side of the flange 7 of the outer shell section 6. The numeral 16 indicates in general the strainer cap of the drain and this cap is of domelike form and is provided in its top with openings 17 and in its sides with openings 18 for the passage of rain water and the entrance 20 of air to provide for free flow of the water into the drain, the lower edge of the cap being provided with notches 19 through which the rain water may flow from the pan 1. The said lower edge or base of the cap 16 is disposed to rest against the outstanding flange 15 of the shell section 14, and the strainer cap is provided exteriorly at intervals in the circumference of its bottom portion with lugs 20 which are notched as indicated by the numeral 21, so as to accommodate brass bolts 22 which are threaded through outstanding lugs or ears 23 upon the flange 7 and into threaded openings 24 formed in the pan 1 adjacent the opening 2 therein, the several component parts of the drain being, in this manner, connected together to constitute a unitary structure.

It will be evident that inasmuch as the section 14 of the shell of the drain is of less diameter than the outer section 6, a dead air space 24 will be provided between the sections, thus insulating the sections so that there will be no likelihood of the formation of water of condensation, upon the surface of the section

6 which might otherwise occur, due to the 45 presence of warm, moist air within the building in which the drain is installed. Furthermore, the section 6 establishes a firm and rigid connection between the drain as a whole and the hub fitting 10, and the section 14 is, therefore, relieved of strain and is better adapted to 50 serve its primary function of conducting the rain water to the hub 10.

It will likewise be evident from the foregoing description of the invention that the parts comprising the drain will not be subjected to stresses or strains due to expansion or contraction of the roof structure, because of the provision of the expansible and contractible bead 5, which bead, as previously explained, likewise serves as an abutment or stop to prevent any of the roofing material reaching the strainer cap 16.

Having thus described the invention, what we claim is:

In a structure of the character described, a drain pipe having its upper end portion enlarged to provide a socket open at its upper end, a roof drain comprising inner and outer tubes, the outer tube having its upper end 70 adapted to be secured to a roof and its lower end portion extending into said socket in spaced relation to the walls thereof and provided with an outstanding annular flange bearing against the walls of the socket, the 75 inner tube being spaced from the walls of the outer tube and having its upper end in air-tight engagement therewith and its lower end portion projecting downwardly and fitting snugly within the drain pipe beneath the 80 socket to form a dead-air space between the tubes, and packing in the socket about the outer tube to firmly hold the same in place.

In testimony whereof we affix our signatures.

THADDEUS J. FLYNN. [L.S.]
JOHN H. FLYNN. [L.S.]
